UNITED STATES PATENT OFFICE.

ALOYSIUS J. CAWLEY, OF PITTSBURGH, PENNSYLVANIA.

RECORD MOLDER.

Application filed October 3, 1919. Serial No. 226,226.

The invention relates to the thermoplastic duplication of sound records, particularly those consisting of a groove on the margin of a motion picture film. A patrinx is formed 5 from the record groove, and is cemented to the motion picture negative film margin. This constitutes a talking picture negative film, as it contains a negative picture record capable of having other records printed from 10 it, and a sound record patrinx capable of impressing the sound record corresponding to the picture record.

By operating the sound record molder in conjunction with a picture printer, a positive talking picture record is obtained consisting of a picture film having a sound record groove on its margin. The impressing of the sound record requires no additional time to that of the picture printing. 20 Much labor and time are thus saved, and an accurate register of the two records obtained, insuring complete synchronism in their reproduction.

This application is a continuation in part 25 of my application for a process of producing a sound record, filed May 2, 1917, Serial Number 165,861.

For a more complete understanding of the invention, reference is to be had to the 30 following description and claims taken in connection with the accompanying drawings which illustrate certain embodiments of the invention, and wherein similar reference characters are employed to designate corresponding parts.

Figure 1 shows a sound record photographically impressed on a photo-sensitive strip, printed from the master sound record on the margin of the negative motion picture film, shown in Figure 1A.

Figure 1A shows a negative film consisting of a photographic picture record having on its margin an undulating sound record line corresponding to the picture record.

Figure 2 at A, B and C shows three cross-sectional views of matrices produced from the sound record line.

Figure 3 shows a patrinx cemented to the 35 margin of the negative film, forming a talking picture negative.

Figure 4 shows the sound record molder impressing a sound record groove in a positive film. It operates in synchronism with 40 a picture printer.

Figure 5 shows the manner in which the

sprockets may be grooved to accommodate the patrinx on the talking picture negative.

Figure 6 shows a negative motion picture film having a photographic sinuous sound record line on its margin which has been built up in relief by the well known chemical means. This is used similar to the combined picture record and corresponding sound record patrinx shown in Figure 3. All of the 45 intermediate stages of producing a patrinx have been thus eliminated.

The sound and picture record are taken synchronously in the camera. This may be done by producing a sinuous line of metallic silver as 18 on negative film A Figure 1A in any of the well known manners, or a sound groove may be impressed directly on the margin by a stylus in the well known manner, also.

Figure 1 shows a sinuous photographic line 18 on the margin of a negative motion picture film A. This may be printed upon a photosensitive strip 17, the printed record being shown at 16. 19' represents the 50 sprocket holes on the ordinary motion picture film, and 19 represents the sprocket holes on the printed strip. Figure 2 shows a bichromated gelatine strip which has been treated with cold water in the well known manner. This has caused ridge 20 to be raised on its surface. This may be hardened by means of chrome alum, tannic acid, formalin, alum, or similar substances. It may be used directly as a patrinx to impress a 55 groove on a celluloid, or similar film. If a silver haloid strip be used, the silver line on the margin of the negative film may be built up chemically so as to form a raised ridge. This ridge on the negative film may be used directly as a patrinx, as shown at 20 in Figure 6.

If the printing be done on bichromated gelatine and this treated with warm water, the unaltered material is dissolved out and the groove 21 is produced, as shown at Figure 2'. If a silver haloid strip is used, the metallic silver of the record line may be dissolved out by chemical treatment, for instance with nitric acid. Or, as stated above, a mechanical sound record groove may be impressed directly on the motion picture film margin by a photographic recording stylus. In any case, after thoroughly drying and hardening the strip, it is 110 placed in contact with a ribbon of soft metal, such as lead, and pressure applied by

rolls, or the like, and a metallic matrix D having a ridge 22 obtained. This is shown at Figure 2^c, and may be used to impress the record upon the margin of the positives.

In practice many positives are produced from the same negative to supply the various film exchanges. In order to facilitate this and also to afford convenience in handling and storing, and also to avoid error in printing sound and picture records in proper register, the matrix D is cemented to the negative film margin as shown in Figure 3. The utility of this will be better appreciated by a study of the next figure.

Figure 4 is a view of a device intended to print a positive picture film from the negative film A, and at the same time impress the sound record in the film. The combined negative and matrix shown in Figure 3 is utilized in this apparatus. The reel 43 containing the positive film 26 is placed on the spindle 47', and the reel 44 containing the negative film A with its matrix D is placed on the spindle 47. Ordinarily the celluloid faces of the films will be thus facing each other, but in case they are not, one or both reels may be turned around, and the film placed over the guiding roll 48 or 48'. In any event the film will always be in a nearly vertical position as shown in the drawing. The films pass between the heated rolls 40^a and 40^b, where pressure is applied in order that the matrix may leave its impression in the celluloid. On their way to those heated rolls the films pass close to, or in direct contact with the metal chamber 41 containing steam or hot water. This insures the films being brought up to the plastic temperature without any necessity of reducing the usual printing speed of the picture printing portion of the apparatus. The films then take opposite directions and pass over the guiding rolls 45 and 45', and from thence to the picture printer. This latter is not all illustrated in the drawing, as any ordinary picture printer can be used here. The only alteration that is necessary is to provide a groove 46 in all of its sprocket wheels as well as in the film gate. However, this may not be really necessary. This is to permit the passage of the matrix without any possible injury to it. The main sprocket of the printer is shown at 25 with its guiding rolls 27 and groove 46. This sprocket is directly under the film gate of the printer. A cross section of the sprocket is also shown in Figure 5. This illustrates the manner in which the matrix D fits into the groove 46, while the gelatine faces of the negative film A and the positive film 26 are in contact during the process of printing. After being exposed in the film gate to light, the two films pass upwards and are wound upon their respective reels in the usual manner. The

positive is then developed and is ready for the reproduction of both pictures and sounds. The sprocket 25 and heated rolls 40^a, 40^b are rigidly connected by a suitable gearing, such as a belt, or sprocket chain, so that the film moves at a uniform speed throughout the apparatus. The guiding rolls 45, 45' may, therefore, be dispensed with, if desired. One form of gearing is, however, illustrated. Two intermeshing pinions 25^a and 25^b are provided between the heated rolls and the sprocket 25 of the picture printer to insure the proper speed. Pinions 40^a and 40^b maintain the heated rolls in step. The rolls and chamber are connected by suitable piping to a source of steam, or other heating medium. In the drawing, the films are supposed to pass downward over the heated chamber and through the heated rolls; after this, they pass to the printer at the top. But the order can be reversed, if desired. In such case it would be necessary to provide the heated chamber below the rolls 40^a and 40^b. Chambers may be provided in both positions and the steam or hot water turned into either according to the direction of motion of the film. It is desirable to heat the matrix as well as the positive film in order to obtain a more satisfactory impression. The power is preferably applied directly to the heated rolls, while they in turn drive the sprocket 25 of the picture printer.

By attaching the matrix directly to the negative and by further using the devices shown in Figures 4 and 5, the difficulties which would ordinarily arise from the use of many feet of metallic or gelatine ribbon, are greatly minimized. Moreover, by means of identification marks on the films, strips and patrices when printing and impressing, the errors due to improper register will be practically eliminated, and perfect synchronism of picture and sound record secured. Also the apparatus combines several tedious and bothersome operations into one.

All positives required to supply film exchanges and the like have their picture record printed and sound record molded in one operation. It only remains to develop the picture record. If desired, during the latter operation, an adhesive water-proof tape can be cemented over the sound groove in order to protect it from the developing bath. Or, it may be coated with a wax-like substance. This is not necessary, however. By combining those various processes to produce unitary results, an immense amount of time and trouble is saved, and possibilities of errors reduced.

Having described my invention, I claim as new and desire to secure by Letters Patent:—

1. The process of duplicating sound records which consists in synchronously moving

the patrinx and blank film, raising the temperature of said film to render it thermoplastic and imposing pressure upon said patrinx and the said film to form an impression of said patrinx in said film.

2. The process of duplicating talking picture records which consists in synchronously moving a talking picture negative and a positive blank film, raising the temperature of said film to render it thermoplastic and imposing pressure upon the patrinx of said negative talking picture and the portion of said film in contact with said patrinx to form an impression of said patrinx in said film; separating said talking picture negative and film, and again bringing them in contact with their gelatine faces in contact, and causing light to pass through the negative picture record of said talking picture negative to impress a developable image on said film, and developing said image.

3. A sound record molder which consists of means for supporting and synchronously moving a sound record patrinx and a thermoplastic film, means for raising the temperature of said film to render it thermoplastic, and pressure rolls to form an impression of said patrinx in said film constituting a sound record groove.

4. A talking picture duplicator which consists of means for supporting and synchronously moving a talking picture negative and a blank film, means for raising the temperature of said film to the thermoplastic state, pressure rolls to form an impression of the patrinx of said talking picture negative constituting a sound record groove; means for intermittently moving said negative and film through a film gate under the action of light to form a developable image of the picture record of said negative upon the sensitive surface of said blank film.

5. A talking picture duplicator which consists of pivots to hold a reel containing a talking picture negative and a reel containing an unexposed motion picture film, suitable gearing to move said film and negative synchronously, heated rolls under pressure synchronously moving and forcing together

said negative and film to form an impression 50 of the patrinx of said negative in the margin of said film, sprocket wheels which separate said negative and film, reverse the directions of said negative and film and bring them with their gelatine faces in contact through 55 a series of sprockets which causes said negative and film to move intermittently pass an exposure aperture under the influence of light to impress a developable image of said picture record.

6. A sound record molder consisting of means for supporting reels containing a talking picture negative and an unexposed motion picture film, means consisting of sprocket wheels and toothed pressure rolls, for 65 moving said negative and film in synchronism, a steam chamber between said film and patrinx of said negative and a steam supply to said rolls to bring said film to thermoplasticity in order that said patrinx may form 70 an impression in the margin of said film constituting a sound record groove.

7. A talking picture record duplicator consisting of means for supporting reels containing a talking picture negative consisting of a motion picture negative carrying a sound record patrinx and an unexposed motion picture film, means consisting of sprocket wheels for moving said negative and film synchronously, means consisting preferably 80 of steam heaters for rendering said film thermoplastic, toothed and grooved pressure rolls to force said patrinx and the margin of said negative film in contact to obtain an impression of said patrinx constituting a sound 85 record groove, sprocket wheels which separate said negative and film and bring their gelatine surfaces in contact, a grooved sprocket which possesses an intermittent motion and feeds said negative and film intermittently through an exposure aperture under the influence of light to produce a developable image of the picture record of said negative, and developing said image to obtain a talking picture positive.
